PREPARATION OF ALKALI METAL DISPERSIONS

Paul F. Warner, Phillips, Tex., assignor to Phillips Petroleum Company, a corporation of Delaware

Application December 30, 1954, Serial No. 478,618

8 Claims. (Cl. 252—309)

This invention relates to the dispersion of alkali metals in a dispersing medium.

Dispersions of alkali metals, particularly sodium, have been known and used for many years. Such dispersions are used as catalysts for many organic reactions, e.g. the production of liquid polybutadiene, metalation reactions, refining of petroleum fractions etc. Several batch methods are given in the art for the preparation of sodium dispersions. These batch methods work well enough when the sodium dispersion is employed in small scale batch reactions and are used immediately after preparation. Sodium dispersions are dangerous to handle and it is desirable to have on hand at any given time only very limited quantities of sodium in the dispersed state. Furthermore, it is extremely difficult to pump and to meter sodium dispersions. With the development of large scale processes, and particularly continuous processes, wherein sodium dispersions are employed it has become highly desirable to be able to prepare these dispersions in a continuous manner.

I have devised a method and apparatus for continuously preparing a dispersion of an alkali metal in an inert liquid by means of which the above mentioned difficulties are overcome or at least mitigated. Broadly speaking, my invention comprises continuously passing molten alkali metal and dispersing medium in metered amounts through a dispersing zone and concomitantly dispersing said metal in said medium.

An object of this invention is to provide a method for preparing a dispersion of alkali metal in a dispersing medium.

Another object of this invention is to provide a method for continuously preparing a dispersion of alkali metal in a dispersing medium and feeding said dispersion to a reaction zone as it is formed.

Another object of this invention is to avoid the use of pumps and meters in handling dispersions of alkali metals in a dispersing medium.

Another object of this invention is to avoid the necessity for storing large quantities of alkali metal in the dispersed state.

Still another object of this invention is to provide apparatus for carrying out the aforesaid objects.

Other objects and advantages of the invention will be apparent to those skilled in the art upon reading this disclosure and the attached drawing.

According to the invention there is provided a method for the preparation of dispersions of alkali metal in an inert liquid which comprises: continuously displacing molten alkali metal from an alkali metal melting zone, with a metered stream of displacing medium, into and through a dispersing zone; simultaneously and continuously passing an inert liquid in a metered amount into and through said dispersing zone; and concomitantly during said passage dispersing said molten metal in said inert liquid.

Further according to the invention there is provided

a combination of apparatus for carrying out the method of the invention.

It is to be noted that the dispersion is prepared in a continuous manner. By thus continuously preparing the dispersion, as needed, the necessity for preparing in advance and storing large quantities of alkali metal in the dispersed state, to be used during the course of a reaction, is avoided. My invention makes it possible to prepare the dispersions as needed and pass same directly to the reaction zone. This feature of the invention is a definite advantage from a safety standpoint as will be recognized by those skilled in the art.

It is also to be noted that the molten alkali metal is displaced, with a metered stream of displacing medium, into and through the dispersing zone. Thus the necessity for a pump capable of handling the molten or dispersed alkali metal is avoided. Furthermore all metered streams are free of dispersed metal, either in the molten or solid state, and can be pumped and metered without difficulty.

A further advantage of my continuous method is that any possibility of agglomeration of the dispersed metal is avoided. Such agglomeration sometimes occurs when the dispersion is prepared batchwise and allowed to stand until used.

The term "alkali metals" as employed herein and in the claims includes the metals sodium, potassium, lithium, rubidium and caesium, and also alloys of two or more such metals with each other, for example, potassium-sodium alloys.

Inert liquids are suitable dispersing mediums. The term "inert liquid" includes any organic liquid that is inert to the alkali metal and has a boiling point above the melting point of the metal to be dispersed therein under the conditions of use. Examples of suitable liquids are xylene, toluene, isoctane, heptane, various petroleum fractions such as light naphtha, Stoddard solvent, refined kerosene etc.

The attached drawing illustrates diagrammatically one combination of apparatus which can be employed to prepare dispersions of alkali metals according to the invention.

Referring now to the drawing the invention will be more fully explained. Reference numeral 10 denotes a vessel containing an oil bath which is maintained at a desired temperature by circulating the oil through an external heater 11 by means of line 12 and pump 13. Other means such as immersed electrical heaters can be employed to heat said oil bath. Mounted within and extending through the top 16 of vessel 10 as shown are two melt tanks 14 and 15. Also mounted within and extending through the top 16 of vessel 10 and positioned between said melt tanks is a dispersing chamber 17. In some instances it is desirable to mount dispersion chamber 17 outside oil bath 10 and thus be able to control the temperature of chamber 17 independently of oil bath 10. Also means other than an oil bath, such as hot gases, electrical resistance heaters etc. can be employed to heat said melt tanks and said dispersion chamber.

A first conduit 18 having a valve 19 therein connects the bottom of melt tank 14 with the lower portion of chamber 17. A second conduit 20 having a valve 21 therein connects the bottom of melt tank 15 with the lower portion of chamber 17. Melt tanks 14 and 15 are closed with removable flange plates 22 and 23 respectively. Extending upwardly from said flange plates 22 and 23 are inlet conduits 24 and 25 having valves 26 and 27 therein, respectively. Displacing medium overflow lines 28 and 29 are connected to inlet conduits 24 and 25 respectively at points above valves 26 and 27. Lines 28 and 29 can be connected to tank 30. Dis-

placing medium inlet lines 31 and 32 are connected to inlet conduits 24 and 25 respectively at points below valves 26 and 27. Extending downwardly through cover plate 22 of melt tank 14 are probes 57 and 58 which comprise a high level and low level indicating system. Said probes are connected through the lead wires shown to a suitable relay system (not shown) which operates a suitable warning or indicating device such as a light or bell (not shown).

Dispersing chamber 17 is closed with a removable flanged cover 33. Mounted on the bottom of cover 33 so as to be positioned in the upper portion of chamber 17 is a gear pump 34 having a suction line 35 extending into the lower portion of chamber 17. Pump 34 is driven by motor 36 mounted on top of cover 33 and operatively connected to said pump by a shaft extending through a suitable packing gland or mechanical seal 37. Pump 34 discharges through nozzle 38 against target plate 39. If desired said target plate can be omitted and the pump discharge directed, from a suitable distance away, against the wall of chamber 17. The invention is not limited to employing a gear pump in chamber 17 as just described. Any suitable dispersing means capable of effecting the desired degree of dispersion can be employed in chamber 17. High speed stirring or agitating means can sometimes be employed. One high speed stirring head which can be employed in some instances is the "Dispersator," commercially available in several sizes from Premier Mill Corp., Geneva, N.Y.

In operation for the preparation of a dispersion of an alkali metal in an inert liquid, for example, sodium in xylene, the system from tank 46 through dispersion chamber 17 and line 51 is filled with xylene to remove oxygen. Conduits 18 and 20 can be purged by opening valves 19 and 21 and permitting a small amount of xylene to flow into melt tanks 14 and 15. If desired the system can be purged with nitrogen admitted through line 40, passed through chamber 17, conduits 18 and 20 and a nitrogen atmosphere maintained in melt tanks 14 and 15 as they are being initially charged with sodium.

The oil bath is brought to operating temperature of approximately 240° F. and the melt tanks 14 and 15 are charged with metallic sodium which soon melts sufficiently to form a liquid seal over the entrance to conduits 18 and 20. Displacing medium, generally a light oil such as refined kerosene, is then pumped from tank 30 through line 42, pump 43, lines 44, 31 and 32 into melt tanks 14 and 15 to fill said tanks and purge said lines and pump 43. After the sodium has melted valves 26 and 45 are closed. Displacing medium is pumped from tank 30 via line 42, pump 43, line 44, valve 50 and line 31 into melt tank 14 to displace molten sodium therefrom via conduit 18 and valve 19 into dispersion chamber 17. Simultaneously with the start, and continuously during the flow of displacing medium into melt tank 14, xylene is passed from tank 46 via line 47, pump 48 and line 49 directly into dispersing chamber 17. Upon starting flow of molten sodium and xylene into chamber 17, pump 34 is started and picks up a mixture of said two liquids through line 35 and discharges same through nozzle 38 against target plate 39, shattering the sodium and dispersing it in the xylene. Upon continued introduction of the sodium and xylene into chamber 17 the dispersion of sodium in xylene is displaced by the two said entering streams into line 51 and is passed to the reaction zone where it is to be employed. When substantially all the sodium has been displaced from melt tank 14, as indicated by probe 58, valve 27 is closed, valves 21 and 45 are opened, whereupon displacing medium is admitted into melt tank 15. Valves 50 and 19 are then closed and molten sodium is displaced from melt tank 15 into and through dispersing chamber 17 as described in connection with melt tank 14. Simultaneously during displacement of molten sodium from melt tanks 14 and 15 the flow of xylene into and

through dispersion chamber 17 is continued, pump 34 is running and thus there is obtained concomitant dispersion of said molten sodium in said xylene during passage of said liquids through chamber 17.

When displacing medium is started into melt tank 15 a new charge of sodium is placed in melt tank 14 by opening valve 26. Melt tank 14 is full of displacing medium which overflows through line 28. When melt tank 15 is substantially empty, as indicated by probe 60, the displacing medium is switched back to melt tank 14 in a manner similar to that described and melt tank 15 is recharged. The system is now on continuous operation. Thus, there is obtained, alternate melting of metallic sodium in, and alternate displacing of molten sodium from, a first section and a second section of a sodium melting zone so as to continuously pass molten sodium from said melting zone into and through a dispersing zone.

During the above operations pressure indicating gages 52, 53 and 54 register the pressure in melt tank 14, melt tank 15 and dispersion chamber 17 respectively. Safety release valves 55 and 56 are provided to release displacing medium into overflow lines 28 and 29 respectively if the pressure in melt tanks 14 or 15 becomes too high. Pressure indicating controller 61 and motor valve 62 can be employed to hold a desired back pressure on the system.

Pumps 43 and 48 are metering pumps and are shown as driven by a common drive 57 powered from a source not shown. Separate drive can be used. Said pumps are set to deliver each liquid at a predetermined fixed rate relative to the weight of sodium it is desired to disperse in a given weight of xylene. For example, if it is desired to prepare an alkali metal dispersion containing 25 percent metal by weight, pump 43 is set to deliver 25 parts by weight to every 75 parts by weight delivered by pump 48. Metering and proportioning pumps of this type can be obtained commercially. Other types of pumps and metering systems can be employed. It is a feature of the invention that by performing the pumping and metering operations on the inert liquid and the displacing medium, increased flexibility in the choice of pumps is obtained. The only requirement is that the pumps chosen have sufficient head to move the liquids through the system and the resulting dispersion into the reaction chamber where the dispersion is to be employed.

The following example further illustrates the invention.

Example

The system was prepared for operation as described above. After the metallic sodium had melted in the melt tanks, displacing medium was started into melt tank 14. Simultaneously, xylene was started into the dispersion chamber and pump 34 in said chamber was started. Operating conditions were as follows:

Feed composition:

Sodium	25 parts by weight.
Xylene	75 parts by weight.
Oil bath temperature	240° F. (approx.).
Nozzle to target distance	0.12 inch (approx.).
Velocity of liquid through nozzle	210 to 240 ft./sec.
Residence time in dispersion chamber, average	1.4 to 1.8 hours.
Circulation rate in dispersion chamber	1.7 gal./min. (approx.).

The residence time is defined as the volume of the dispersion chamber divided by the total volume of liquids charged to said chamber. When the sodium had been displaced from melt tank 14 the displacing medium was switched to melt tank 15 and a fresh charge of sodium was melted in melt tank 14 as described. Alternate melting of metallic sodium in, and alternate displacing of

molten sodium from, melt tanks 14 and 15 was continued during the length of the run. The first dispersion product was low in sodium content due to the dispersion chamber being full of xylene at the start of the run. This could have been compensated for by charging the sodium at a higher initial rate. After the system was lined out a sodium dispersion having a composition of 25 percent by weight sodium and 75 percent by weight xylene and an average particle size of 5-10 microns was obtained.

Repeated runs, employing substantially the apparatus and modus operandi described above, have demonstrated that sodium dispersions having a sodium concentration up to at least 50 percent by weight, and an average particle size of at least 5-10 microns, can be prepared continuously and regularly without difficulty.

If desired dispersion aids and dispersion stabilizers can be employed by injecting them into the inert liquid prior to dispersing the metal therein. However, it is a feature of the invention that inasmuch as the dispersion can be prepared as needed and used immediately, the need for dispersion stabilizers is greatly reduced or eliminated.

Operating conditions of temperature and pressure will depend upon the melting point of the metal being dispersed and the boiling point of the inert liquid in which the metal is being dispersed. Generally the temperature will be in the range of 20 to 40° F. above the melting point of the metal.

The pressure will depend to some extent upon the process in which the dispersion is being used. It is preferred to operate the dispersing system at a pressure higher than that at which the process wherein the dispersion is used is carried out. The pressure must be high enough to maintain the inert liquid in liquid phase at the conditions of operation of the dispersing system. The choice of proper operating temperatures and pressures will be readily understood by those skilled in the art in view of this disclosure.

Materials of construction generally can be selected from those available commercially. Mild steel can be used in most instances. Gasketing and packing materials should be inert to sodium. Halogenated materials should not be used.

Caution should be exercised in working with and preparing alkali metal dispersions. All equipment should be clean and dry. Since these dispersions sometimes ignite on exposure to air such exposure should be avoided. Removal of the inert liquid as by evaporation or by capillary action on contact with textile materials, such as clothing, leaves a residue of finely divided metal which may ignite spontaneously.

As will be evident to those skilled in the art, various modifications of the invention can be made, or followed, in the light of the above disclosure and the appended claims, without departing from the spirit or scope of said disclosure and said claims.

I claim:

1. A method for the preparation of a dispersion of an alkali metal in an inert organic dispersing medium which is inert to and has a boiling point higher than the melting point of said alkali metal, which method comprises, in combination, the steps of: continuously displacing a measured amount of a molten alkali metal from an alkali

metal melting zone with a like measured amount of a stream of light oil displacing medium directly into and through a dispersing zone; simultaneously and continuously passing a measured amount of said dispersing medium in a separate stream directly into and through said dispersing zone; and concomitantly, during passage of said streams through said dispersing zone, dispersing said streams through said dispersing zone, dispersing said molten metal in said dispersing medium.

2. A method according to claim 1 wherein said alkali metal is sodium.

3. A method according to claim 1 wherein said alkali metal is potassium.

4. A method according to claim 1 wherein said alkali metal is rubidium.

5. A method according to claim 1 wherein said alkali metal is lithium.

6. A method according to claim 1 wherein said alkali metal is caesium.

7. A method for the preparation of alkali metal dispersions in an inert organic dispersing medium which is inert to and has a boiling point higher than the melting point of said alkali metal, which comprises, in combination, the steps of: continuously pumping a stream of oil at a predetermined fixed rate into an alkali metal melting zone so as to continuously displace a corresponding amount of molten alkali metal directly into and through a dispersing zone; simultaneously and continuously pumping, at a predetermined fixed rate, a separate stream of said dispersing medium directly into and through said dispersing zone, each of said predetermined fixed rates being determined by the weight of said metal to be dispersed in said dispersing medium; and concomitantly dispersing said molten alkali metal in said dispersing medium during said passage of said streams through said dispersing zone to form a dispersion of said metal in said medium.

8. A method for the preparation of a sodium metal dispersion in xylene, which method comprises, in combination, the steps of: alternately melting metallic sodium in, and alternately displacing metallic sodium from, a first sodium melting zone and a second sodium melting zone

30 so as to continuously pass a stream of molten sodium from at least one of said melting zones directly into and through a dispersing zone, said molten sodium being displaced from said melting zones in a measured amount by passing a like measured amount of a light oil displacing

35 medium into said melting zones; simultaneously and continuously passing a measured amount of said xylene directly into and through said dispersing zone; concomitantly, during passage of said streams through said dispersing zone, dispersing said molten sodium in said xylene to form

40 a dispersion; and passing said dispersion directly to a reaction zone.
